UNITED STATES PATENT OFFICE.

JOHN R. GAMMETER, OF AKRON, OHIO, ASSIGNOR TO THE B. F. GOODRICH COMPANY,
OF NEW YORK, N. Y., A CORPORATION OF NEW YORK.

PRESS FOR HORIZONTAL VULCANIZERS.

1,210,926.

Specification of Letters Patent.

Patented Jan. 2, 1917.

Application filed October 5, 1916. Serial No. 123,982.

To all whom it may concern:

Be it known that I, JOHN R. GAMMETER, a citizen of the United States, residing at Akron, in the county of Summit and State 5 of Ohio, have invented certain new and useful Improvements in Presses for Horizontal Vulcanizers, of which the following is a specification.

This invention relates principally to an 10 apparatus for vulcanizing, molded rubber articles such as pneumatic tires in horizontal vulcanizing chambers to which steam is admitted to surround and heat the molds.

Heretofore it has been the practice in 15 using vulcanizers of this type to employ molds, the halves of which are secured together by bolts, whereas in vertical pot vulcanizers it is customary to use a hydraulic press acting on a stack of boltless molds and 20 thus, among other savings, to effect a considerable reduction of time and labor in opening and closing the molds. As heretofore constructed however, the inclosed vertical vulcanizing presses have been objectionable on account of their height and comparative lack of accessibility to the operating parts.

The object of my present invention is to 25 provide a novel form of press, particularly adapted for use in horizontal vulcanizers, thus permitting the employment of boltless molds and quicker charging and discharging methods for this type of vulcanizer.

A further object is to provide such a press 30 with novel fluid piping to the individual molds, thereby permitting, for example, the use of internal or outwardly-acting fluid pressure in the molding of the tires.

Of the accompanying drawings, Figures 1 35 represents a plan view, partly broken away, showing a horizontal vulcanizer and a train of press cars on the outside thereof, all organized according to my invention. Fig. 2 represents a side elevation of the same with 40 the floor in section. Fig. 3 represents a horizontal section of the vulcanizer and a portion of the train showing one of the cars with its upper press member removed, exposing the top of a stack of molds. Fig. 4 45 represents an end view of the vulcanizer showing a press car therein, partly in section on the line 4—4 of Fig. 3, together with a stack of tire molds, one of which is shown in full lines and the others in broken lines.

In the drawings, 10 is a cylindrical horizontal vulcanizer body of ordinary type, with horizontal swinging door 11 hinged at 12. A pair of rails 13, forming a track or railway, is laid in the bottom of the vulcanizer and extends outside of and in line therewith a considerable distance along the floor 14 of the vulcanizing room to permit the loading and unloading of the press cars. A section 13^a of this track immediately in front of the vulcanizer is made removable to 55 permit the swinging of the vulcanizer door 11. 15, 15 are a series of press cars connected together in a train and adapted to be hauled into and out of the vulcanizer. The hauling is done by means of a rod 16 shown 60 in Fig. 2 which is connected with the foremost car of the train and hooked onto a propelling chain 17 which passes around a pair of pulleys 18, 19. The shaft 20 of pulley 18 is connected by suitable gearing 21 to an 65 electric motor 22, which is preferably reversible so as to move the train in either direction without requiring the rod 16 to be shifted from one stretch of the chain to the 70 other.

Each car includes a platform 23 mounted on four flanged wheels 24 which run on the rails 13, and the cars are coupled together by providing their adjacent ends respectively with a pair of arms 25 located relatively far apart and open or slotted on their under sides so as to hook over the ends of one of the wheel axles 26, outside of the wheels 24, and a second pair of arms 27 located relatively near together and similarly 85 open or slotted underneath so as to hook over said axle between the wheels, there being thus between each pair of cars 15 an axle 26 and a pair of wheels 24 common to the two cars. This arrangement reduces the 90 number of wheels and axles required, permits them to be readily removed from the cars, and dispenses with separate couplings between the cars, since the axles and arms 95 act as couplings.

Figs. 3 and 4 show in detail the construction of the press cars. The upper side of the platform 23 forms the lower press member for the stack of tire molds 28, and the underbody of said platform is formed with 100 a downwardly-open shallow cylinder 29 of relatively large diameter. In this cylinder is located a piston 30 having a suitable pack-

ing 31 on its edge, and also having a central rod or stem 32 which passes through a tubular guide 33 and a stuffing-box 34 on the platform 23.

5 The top press plate is the head or cap 35 of a mushroom-shaped member provided with a stem 36 which connects with the upper end of the piston rod 32 by a screw joint 37, so that said member may be uncoupled and

10 lifted out of the way when tire molds are to be loaded upon or unloaded from the press car. The head 35 is provided with a pair of suspension loops 38 for connecting it with the hook of a hoisting chain.

15 Said head and its stem 36 are made hollow and perforate, that is, with an open-topped central cavity 39 and lateral openings 40, 41, permitting access of steam to the interior of the mold stack.

20 It will be noted that the downwardly-acting cylinder and piston in the base of the press, together with a detachable mushroom top member whose stem traverses the interior of the mold stack, provide a very 25 compact structure suited to the restricted vertical dimensions of the ordinary horizontal tire-vulcanizing chamber, the piston necessarily having a short stroke in order to afford maximum vertical stack capacity. If 30 the batch of tires to be vulcanized on a car is less in number than a complete stack of molds, "dummies" or empty molds may be used to fill up.

42 is a fluid passage for charging and 35 exhausting the cylinder 29, the said passage connecting by a curved pipe 43 under the car platform with a trunk pipe 44 which runs longitudinally of the train along one side thereof, and is formed in sections attached to the several cars and connected by 40 couplings 45 between the cars. On the floor of the vulcanizer 10 is a supply pipe 46, preferably sinuous as shown in order to make it flexible and allow some variation in 45 the position of the outer end coupling. Said pipe has a stop-valve 47 at its front end, near the entrance to the vulcanizer, and a union coupling 48 for detachably connecting it with the train pipe 44. The latter 50 has a shut-off valve 49 for the principal purpose of retaining the pressure in the press cylinders after the latter have been charged outside of the vulcanizer by means of a pipe 50 shown in Fig. 1. This pipe is 55 provided with a shut-off valve 50^a and connects with the train pipe 44 through one branch of a stationary T-section of pipe, 50^b, to the opposite branch of which is connected a vacuum pipe 50^c provided with a 60 shut-off valve 50^d. 50^e is a valved waste branch leading from the pipe section 50^b.

The tire molds 28 are of the ordinary type used in vertical vulcanizing presses, being made of two halves without bolts, and adapted 65 to be closed tightly upon the tire casing

by means of axial pressure exerted by the press. These molds may be used with cores either of the ordinary type or of the internal fluid-pressure type, the latter being particularly adapted to the curing of cord tires.

Fig. 4, for example, represents an endless metal filler or core ring 51 for location between the halves of the mold and the beads of the tire casing 52, to mold and pack the latter, and a flexible-walled annular bag or

75 mandrel 53 located within the interior of the tire casing and provided with a branch supply and exhaust pipe 54. The latter is adapted to be connected by a union nut 55 with one of a series of copper pipes 56, leading

80 from a manifold 57 on the car platform 23, the several pipes 56 terminating at different heights for the purpose of connecting with the individual molds of the stack.

85 58 is a branch supply pipe connecting with the manifold 57 and continued in the form of a curved pipe 59 which extends under the car platform. Pipe 59 connects with a

86 trunk train pipe 60 similar to the pipe 44, furnished with couplings 61 between the cars. 90 Pipe 60 connects by a separable union 62 with a sinuous pipe 63, similar to the one 46, lying on the bottom of the vulcanizer and having a band-valve 64 at its front end.

95 In the operation of my invention, assuming that the train of press cars is withdrawn from the vulcanizer, and the upper press member 35 on each car is removed for the

100 purpose of loading the tire molds on the cars, said molds are stacked one at a time on the platform 23 of a car, and as each mold is put in place, its internal-pressure pipe 51 is connected with one of the copper pipes 56 by means of the coupling 55. When

105 the stack is complete the upper press member 35 is lowered into place and its stem by means of the coupling 37, is screwed onto the piston rod 32. Owing to the short stroke of the piston and the fact that the mold halves require considerable pressure in order

110 to close them on the tires, the coupling of the upper press member upon the piston-rod, and the closing of the press, are preferably performed in stages. All of the press

115 cars being loaded and their upper press members 35 screwed down as far as possible with a hand-bar, a connection is made between the train pipe 44 and the stationary

120 hydraulic pipe 50, and water pressure is admitted to the several cylinders 29, thereby forcing down the pistons 30 and causing a downward axial pressure to be exerted

125 upon the stack of molds by means of the press member 35, whereby the two halves of each mold are pressed together or toward each other. Then the supply from pipe 50

130 is shut off, the press cylinders relieved through the waste pipe 50^e, the press members 35 screwed farther down by hand bars, and the pressure again applied. Generally

- two stages will suffice, and when the molds are fully closed the hydraulic pressure is held in the cylinders by shutting the valve 49. The train pipe 44 may then be uncoupled from the external pressure line and the train 16 run into the vulcanizer 10 by means of the rod 16 and chain 17 operated by the electric motor 22, whereupon the train pipes 44 and 60 are connected with the supply pipes 46 and 63 in the vulcanizer and pressure turned on to operate the presses and inflate the tires. The track section 13^a being then removed, the vulcanizer door 11 is closed and locked, and steam is turned on to the interior of the vulcanizer from a suitable source of supply (not shown) to cure the tires. After vulcanization is complete, the steam is turned off, the door 11 opened, the pipes 46 and 63 disconnected, the track section 13^a replaced, and the train of press cars run out of the vulcanizer. The upper press members are then retracted, either by applying a vacuum to the several cylinders 29, through the train pipe 44 and the vacuum pipe 50^c, so that the pistons 30 are raised by atmospheric pressure acting on their lower sides, or by mechanical means not shown in the drawings, adapted to push upwardly upon the exposed lower faces of the pistons. Thereupon the top press member 35, on being unscrewed from the piston rod, may be lifted out of place with suitable chain tackle, the pipes 56 uncoupled from the molds one-by-one, and the molds lifted off and pried open.
- I am aware that horizontal vulcanizers have been equipped with a battery of hydraulic presses permanently associated with the vulcanizer and operating through the floor thereof upon a car of long molds such as used for solid carriage tires, but I believe myself to be the first to utilize the ordinary horizontal open-steam vulcanizing chamber in connection with a portable press for pneumatic tire molds. It is evident that the details of embodiment of the invention herein described and claimed may be widely varied. It is also evident that the novel features of my vulcanizing press may be utilized wherever applicable, regardless of the particular mode in which the heating medium is applied to the molds.
- I claim:
1. A vertical vulcanizing press comprising a base or platform for supporting a stack of molds, an upper press-member movable toward said base to clamp the molds thereon, and a cylinder associated with said base and having a downwardly-acting piston detachably connected with said upper press member.
  2. A vertical vulcanizing press comprising a base or platform constituting a lower support for a stack of molds and having associated therewith a downwardly-acting fluid-pressure cylinder and piston, said piston having a stem passing through a guide on the base, and an upper press member having a stem detachably connected with said piston stem.
  3. A vertical vulcanizing press comprising a base provided with a lower press member and a downwardly-open cylinder having means for admitting and discharging the working fluid, a piston in said cylinder exposed to atmospheric pressure on its lower side, and an upper press member connected with said piston.
  4. Vulcanizing apparatus comprising a horizontal open-heat vulcanizing chamber, and a car adapted to be run into and out of said chamber and provided with a press for acting on a stack of molds carried by the car.
  5. Vulcanizing apparatus comprising a horizontal vulcanizing chamber, a car movable into and out of said chamber and carrying a fluid-operated mold press, and a fluid-supply conduit having a separable coupling for attaching it to the press when located within said chamber.
  6. Vulcanizing apparatus comprising a horizontal vulcanizing chamber, a series of cars provided with fluid-operated mold presses and coupled together in a train which is movable into and out of said chamber, and means to supply fluid under pressure to the presses of the cars within said chamber.
  7. Vulcanizing apparatus comprising a vulcanizing chamber, a fluid-operated mold press movable into and out of said chamber, means to supply working fluid to operate said press when located within said chamber, and means to supply working fluid to operate said press when located outside of said chamber.
  8. Vulcanizing apparatus comprising a horizontal vulcanizing chamber, a car movable into and out of said chamber and provided with a fluid-operated mold press, a fluid-supply conduit having a detachable coupling within said chamber for operating said press during vulcanization, and a second fluid conduit having a detachable coupling external to said chamber for operating said press when the car is out of the chamber.
  9. Vulcanizing apparatus comprising a vulcanizing chamber, a fluid-operated mold press movable into and out of said chamber, means for supplying fluid under pressure to said press while in the chamber, and means for applying pressure to said press to open the latter when located outside of said chamber.
  10. Vulcanizing apparatus comprising a horizontal vulcanizing chamber, a loading floor in front of said chamber, a wheeled car movable into and out of said chamber and over said floor, a fluid-operated mold press

carried by said car, and a fluid-supply pipe adapted to be coupled to the press when located in said chamber.

11. Vulcanizing apparatus comprising a base for supporting a stack of annular molds, a piston and cylinder associated with said base, a movable press member for engaging the upper end of the mold stack, and a connection between said piston and press member adapted to traverse the hollow interior of the mold stack.

12. Vulcanizing apparatus comprising a base for supporting a stack of annular molds, a cylinder and piston associated with said base, a series of pipes mounted on the base and having separable couplings for connection with the individual molds, and

an upper press member connected with the piston and removable to permit loading and unloading of the molds and allow access to said couplings.

13. Vulcanizing apparatus comprising, in combination, a base having a cylinder and piston associated therewith, a stack of annular molds supported on said base, an upper press member having a stem traversing the interior of the mold stack and separably connected with the piston, and means within the interior of the mold stack for supplying fluid under pressure to the respective molds.

In testimony whereof I have hereunto set my hand this third day of October, 1916.

JOHN R. GAMMETER
